LOOM TEMPLE WITH THREAD CUTTING MECHANISM

Fredric E. Douglas, Hopedale, Mass., assignor to
Draper Corporation, Hopedale, Mass., a corporation of Maine

Application May 8, 1933. Serial No. 669,881

8 Claims. (Cl. 139—266)

The present invention relates to thread cutting mechanism for loom temples and has more particular reference to such mechanisms having a moving thread cutting blade which is rendered inoperative after it has operated a predetermined number of times.

Thread cutting mechanisms of the type mentioned are usually connected with the filling replenishing mechanism of an automatic filling replenishing loom, so as to be put into operation immediately after each replenishment of the filling supply, which is usually the only time threads to be cut are presented to the thread cutting mechanism. Existing devices for rendering the thread cutting blade inoperative after it has operated the required number of times are, in general, too complicated to be of material practical value, or are not sufficiently positive in operation and consequently rendered unreliable by the shock and jar incident to operation of the loom.

Accordingly, it is the principal object of my invention to provide a loom temple carrying a thread cutting mechanism which includes a movable cutting blade and a simple, reliable means acting positively to render the cutting blade inoperative after a predetermined number of operations thereof.

The mechanism which I have devised for the foregoing purpose includes a toothed ratchet element and a pair of toothed pawl elements cooperating in a novel manner, to positively produce relative movement therebetween which positive movement is utilized to effect the locking of the thread cutting blade out of operation. In the preferred form, the elements are positioned substantially in a single plane parallel to and closely adjacent the plane of the thread cutting blade, whereby the entire mechanism is extremely compact and may easily be covered by a cover plate for protection from lint and dust.

For a detailed disclosure of the preferred embodiment of my invention, reference may be had to the accompanying drawings, of which:

Fig. 1 is a plan view of a temple head to which the invention has been applied;

Fig. 2 is a view similar to Fig. 1, but with parts broken away and appearing in section as indicated by line 2—2, Fig. 3;

Fig. 3 is a vertical sectional view, taken approximately on line 3—3, Fig. 1, but to a larger scale; and

Fig. 4 is a view similar to Fig. 3 but showing the parts in the positions they occupy when the thread cutting blade is locked out of operation.

55 The temple to which my invention has been

applied is of conventional design except where modified to cooperate with the novel form of thread cutting mechanism. Such temple includes a bar 1, adapted to be received in the conventional housing mounted on the breast beam of 60 the loom (not shown). The bar 1 carries at its rearward end a head comprised of a cap 2 and a base 3 held together by means including a screw S. A temple roll or rolls (not shown) may be housed in the temple head, and the base 3, which 65 is integral with the bar 1, is provided with an integral depending heel 4 by which the temple may be reciprocated.

The thread cutter proper which I have chosen to illustrate my invention is comprised of a stationary ledger blade 5 and a movable thread cutting blade 6 mounted in a guideway 7 in the temple head. The guideway is substantially in a vertical plane and extends through the temple head from front to rear thereof.

The ledger blade 5 shown bears against one vertical wall of the guideway and is of the form shown in my copending application Serial No. 625,763, filed July 29, 1932, now Patent Number 1,914,663, granted June 20, 1933. The blade 6 80 will be recognized as being of conventional form, the same being confined to rocking and sliding movements in the guideway 7 and being constituted by a casting on the rear end of which is formed a cutting tip 8 and on the forward end 85 of which is formed a depending heel 9 carrying a stud 10. A coil spring 11 has a depending arm (not shown) for engagement with the stud 10 in the usual manner, for urging the blade 6 rearwardly to the position shown in Fig. 3, the blade 90 being given its forward cutting stroke by the usual lay bunter.

It is noted at this time that other conventional thread cutting devices may be substituted for those shown, the principal requisite, so far as my 95 invention is concerned, being that such devices include a movable thread cutting blade which in its operation is confined to movement substantially in a vertical plane.

The cap 2 has been extended forwardly and 100 upwardly at one side of the bar 1 to form a housing 12 within which is formed a substantially vertical guideway 13. A cover plate 14 may be secured to the vertical face of the cap and housing, to cover and conceal certain parts herein- 105 after described.

A locking member 15, constituted in the present instance by a flat bar having a flanged edge 16, is positioned vertically in the guideway 13 and is vertically slidable therein. The uppermost 110

position of the member 15 is substantially above the position in which it appears in Fig. 3, while its lowermost position shown in Fig. 4, is a locking position. In the locking position of the member 15 the inclined edge 17 thereof engages the stud 10 and locks the thread cutting blade 6 in its forward position against the action of spring 11, thus rendering the blade inoperative.

The locking member 15 may be raised to its uppermost position by any suitable means such as a lever 18 pivoted on a screw 19 and engaging a pin 20 in the top of member 15. The lever 18 is operable at the desired time by connections to the replenishing mechanism (not shown) or any suitable part thereof, such connections being not illustrated or described as they form no part of the present invention and, in addition, are well known in the art.

The locking member 15 is moved, step by step, from its uppermost position to locking position by a device which is of my invention, this device being constituted, in its simple form, by three elements one of which is a toothed ratchet element and two of which are toothed pawls. One of these elements is fixed, one is connected to the locking member and one is regularly oscillated. It will be apparent that, from one view point, it makes little difference which of the three elements is connected to the locking member or which is the fixed element, but I have illustrated and will now describe the specific embodiment which I consider the most desirable.

In such embodiment the ratchet element 21 is constituted by a vertically extending toothed rack having a toothed surface 22 and is movably mounted on the locking member 15, as by being pivotally suspended from a screw 23 in the member 15. Thus, the rack is positioned, and operates, in a plane parallel to the plane of the thread cutting blade 5. A spring 24, having its upper end fixed in the rack and its lower free end bearing against the flange 16, constitutes means for yieldingly urging the rack rearwardly toward the fixed pawl 25.

The pawl 25 consists of a flat metal plate provided with a forwardly extending tooth 26 adapted to successively contact the teeth of the rack, in a manner hereinafter described. The pawl 25 is positioned in the plane of rack 21, being fixed to the face of the cap 2 by a screw 27.

The oscillating pawl 28 consists of a flat bar carrying a tooth 29, the point of which is spaced, lengthwise of the rack, from the point of tooth 26. The bar is pivotally suspended from a pin 30 in bracket 31 which is fixed to the upper forward portion of housing 12 as by a screw 32. The lower end of the pawl 28 is provided with a slot 33 engaging over the stud 10 on the thread cutter heel 9, whereby the pawl is oscillated in synchronism with the movements of the thread cutting blade 6. The tooth 29 and the tooth 26 are comparatively thin and, while they overlap slightly, they are nevertheless both substantially in the same plane as the rack 21.

It will be noted that while I have shown the teeth 29, 26 as spaced vertically along the rack a distance equal to about half the pitch distance of the rack teeth, they may be otherwise spaced, as even specific expressions of my invention require only that this spacing be other than an even multiple of the pitch distance of the rack teeth. This may be more readily understood after a detailed study of the operation of the mechanism, which is as follows:

When the locking member is raised to its upper-

most position, which is some distance above that shown in Fig. 3, the thread cutting blade 6 is put in operation. As the blade 6 is moved forwardly (to the left in Figs. 3 and 4) the tooth 29 will be moved horizontally into contact with one of the rack teeth 22 and will swing the rack forwardly against the action of spring 24 until the rack teeth are clear of the fixed pawl 25, 26. Then, since the lower inclined surface of tooth 29 only partially overlaps the upper inclined surface of the contacting rack tooth, continued forward movement of the tooth 29 will serve to cam the rack downward a distance equal to about half the thickness of the rack tooth. The blade 6, and thereby the pawl 28, are then returned rearwardly, whereupon spring 24 will urge the rack rearwardly and the lower inclined surface of the fixed tooth 26 will engage the upper inclined surface of the next rack tooth and, under the influence of the spring 24, will be cammed downwardly a further half-tooth distance.

The alternate, horizontal engagement of the pawls with the rack is continued so long as the thread cutting blade remains in operation and each time the blade makes one complete stroke the rack, and thereby the locking member, will be positively forced downwardly toward the locking position of the latter. It will be noted that the upper surface of the top rack tooth is somewhat longer than the others, and the final locking movement of the rack and locking member will be greater than the normal step by step movement thereof, but this is but a matter of expediency. However, the final movement of the locking member results in edge 17 thereof engaging stud 10 and locking all the parts, including the cutting blade 6, in the position shown in Fig. 4.

Having fully disclosed the preferred embodiment of my invention, I claim:

1. The combination of a loom temple with a thread cutting mechanism carried thereby, said thread cutting mechanism including a thread cutting blade operating in a vertical plane, a locking member operating in a plane parallel to the plane of said thread cutting blade and movable to and from locking position wherein it locks the said blade out of operation, a toothed ratchet element and a pair of toothed pawl elements, which elements are positioned substantially in a single plane parallel to the plane of said thread cutting blade and of which elements one is fixed and one is connected to said locking member, and means for relatively moving said elements transversely of the direction of movement of said member to positively move the latter step by step to locking position.

2. The combination of a loom temple with a thread cutting mechanism carried thereby, said thread cutting mechanism including a thread cutting blade operating in a vertical plane, a locking member operating in a plane parallel to the plane of said thread cutting blade and movable vertically to and from locking position wherein it renders the said blade inoperative, a toothed rack movably mounted on said member and extending substantially parallel thereto, a fixed pawl and a movable pawl spaced along said rack, and means for alternately engaging said pawls horizontally with the teeth of said rack for positively moving the rack and thereby the locking member, toward locking position of the latter.

3. The combination of a loom temple with a thread cutting mechanism carried thereby, said thread cutting mechanism including a thread cut-

- ting blade operating in a vertical plane, a locking member operating in a plane parallel to the plane of said thread cutting blade and movable vertically to and from locking position wherein it renders 5 the said blade inoperative, a toothed rack movably mounted on said member and extending substantially parallel thereto, a fixed pawl and a movable pawl spaced along said rack a distance other than an even multiple of the pitch distance 10 of the rack teeth, and means for alternately engaging said pawls horizontally with the teeth of said rack for positively moving the rack and thereby the locking member, toward locking position of the latter. 15 4. The combination of a loom temple with a thread cutting mechanism carried thereby, said thread cutting mechanism including a thread cutting blade operating in a vertical plane, a locking member operating in a plane parallel to the 20 plane of said thread cutting blade and movable vertically to and from locking position wherein it renders the said blade inoperative, a toothed rack pivotally mounted on said member and extending substantially parallel thereto, a fixed pawl and a movable pawl spaced along said rack a distance less than the pitch distance of the rack teeth, and means for alternately engaging said pawls horizontally with the teeth of said rack for positively 25 moving the rack and thereby the locking member, toward locking position of the latter. 30 5. The combination of a loom temple with a thread cutting mechanism carried thereby, said thread cutting mechanism including a thread cutting blade operating in a vertical plane, a substantially vertically extending locking member positioned by the side of said thread cutting blade and movable vertically to and from locking position wherein it locks the said blade out of operation, a toothed rack supported by said member, a fixed pawl and a movable pawl for positively moving said rack and thereby the locking member toward locking position of the latter, and means for oscillating said movable pawl in synchronism with the movements of the said thread cutting 35 blade. 40 6. The combination of a loom temple with a thread cutting mechanism carried thereby, said thread cutting mechanism including a thread cutting blade operating in a vertical plane, a substantially vertically extending locking member posi- 45 50 55 60 65 70 75 80 85 90 95 100 105 110 115 120 125 130 135 140 145 150

tioned by the side of said thread cutting blade and movable vertically to and from locking position wherein it locks the said blade out of operation, a toothed rack movably mounted on said member, a fixed pawl and a movable pawl positioned substantially in the plane of said rack and spaced therealong, and means for successively engaging the said pawls with the teeth of the said rack to positively move the rack, and thereby the locking member, toward locking position of the latter. 7. The combination of a loom temple with a thread cutting mechanism carried thereby, said thread cutting mechanism including a thread cutting blade operating in a vertical plane, a substantially vertically extending locking member positioned by the side of said thread cutting blade and movable vertically to and from locking position wherein it locks the said blade out of operation, a toothed rack pivoted to said member and having a vertically extending toothed surface, a fixed pawl and a movable pawl positioned substantially in the plane of said rack and spaced therealong a distance other than in even multiple of the pitch distance of the rack teeth, means for yieldingly urging said rack toward the said fixed pawl, and means for oscillating said movable pawl horizontally into and out of contact with the rack teeth to thereby positively move the rack and the locking member toward locking position. 8. The combination of a loom temple with a thread cutting mechanism carried thereby, said thread cutting mechanism including a thread cutting blade operating in a vertical plane, a locking member positioned adjacent said thread cutting blade and movable to and from locking position wherein it engages said blade and locks the latter out of operation, a toothed rack having connections to said member, a fixed pawl and a movable pawl spaced along said rack a distance other than an even multiple of the pitch distance of the rack teeth, and means for alternately engaging said pawls with the teeth of the rack in a direction at right angles to the length of the rack, such engagement serving to cam the rack lengthwise in a direction to move said member toward locking position.
